US0D1023032S

(12) **United States Design Patent** (10) **Patent No.:** **US D1,023,032 S**
(45) **Date of Patent:** **** Apr. 16, 2024**

(54) **DISPLAY SCREEN WITH GRAPHICAL USER INTERFACE FOR DATA VISUALIZATION**

(71) Applicant: **Constellation Generation Services, LLC**, Baltimore, MD (US)

(72) Inventor: **Sanwar Azam Sunny**, Kansas City, MO (US)

(73) Assignee: **Constellation Generation Services, LLC**, Baltimore, MD (US)

(**) Term: **15 Years**

(21) Appl. No.: **29/831,327**

(22) Filed: **Mar. 18, 2022**

(57) **CLAIM**

The ornamental design for a display screen with graphical user interface for data visualization, as shown and described.

DESCRIPTION

The FIGURE is a front view of a display screen with graphical user interface for data visualization, showing the design.

The inner broken line rectangle illustrates the display screen and forms no part of the claimed design. All other broken lines illustrate an electronic device and form no part of the claimed design.
